BACKSPLASHER UNIT FOR SINKS

Olle E. Haggstrom, Louisville, Ky., assignor to
General Electric Company, a corporation of
New York

Application October 26, 1953, Serial No. 27,312

Term of patent 14 years

(Cl. D4—2)

To all whom it may concern:

Be it known that I, Olle E. Haggstrom, a citizen of the United States, residing at Louisville, in the county of Jefferson, Commonwealth of Kentucky, have invented a new, original, and ornamental Design for a Backsplasher Unit for Sinks, of which the following is a specification, reference being had to the accompanying drawing forming a part thereof, in which:

Fig. 1 is a perspective view of a backsplasher unit for sinks embodying my new design;

Fig. 2 is a vertical sectional view thereof, taken in the direction of the arrows along the line 2—2 in Fig. 1.

The dotted line disclosure of light tube, faucet

and sink member are shown only for purposes of illustration.

I claim:

The ornamental design for a backsplasher unit for sinks, as shown and described.

OLLE E. HAGGSTROM.
